BAG MACHINE

Filed Dec. 31, 1923

UNITED STATES PATENT OFFICE.

AUGUST BECKMANN, OF BRYN MAWR, PENNSYLVANIA, ASSIGNOR TO THOMAS M. ROYAL & CO., OF PHILADELPHIA, PENNSYLVANIA, A CORPORATION OF PENNSYLVANIA.

BAG MACHINE.

Application filed December 31, 1923. Serial No. 683,818.

My invention relates to machines of the type in which bellows-folded tubes are formed from a web of paper, which tubes are subsequently severed into bag blanks and then presented to bottom forming mechanism, all of such operations being performed automatically upon a continuous web (or webs) of paper fed to the machine from a suitable supply.

One object of my invention is to provide bag machines of this character with means whereby the paste can be uniformly applied to the edge of the web subsequently formed into the bellows-folded tube. In order to effect this result, I preferably gear the paste roll to one of the idler rolls over which the web of paper passes; the movement of which idler roll is effected by the movement of the web, and by gearing said paste roll to an idler roll that is driven by the paper so that said paste roll is positively moved, there is an assurance that a line of paste will be applied to the moving web of paper in the proper manner.

A further object of my invention is to provide means for spreading the line of paste so applied into a thinner film, so as to insure a smooth seam which may be closed by the application of plain surfaced rolls which may also serve as the draft rolls for effecting movement of the bellows-folded tube.

A further object of my invention is to provide means whereby a special type of bag may be produced from the bellows-folded tube; the latter being provided with a side seam.

And a still further object of my invention is to provide a special draft roll for effecting movement of the bellows-folded tube to the point where the latter is severed into blanks which are then passed to bottom forming mechanism to complete the formation of the bag.

These and other features of my invention are more fully described hereinafter; reference being had to the accompanying drawings, in which:

Figure 1, is a plan view, more or less diagrammatic, of sufficient of the mechanism of a paper bag machine to show the paste-applying means and the adjacent elements for forming a bellows-folded tube from a continuous web of paper, to illustrate my invention.

Fig. 2, is a side elevation, more or less dia-

grammatic, of the mechanism shown in Fig. 1.

Fig. 3, is a view in elevation of the draw rolls which I may employ with my improved bag machine.

Fig. 4, is a plan view of a portion of the web, showing the lines of fold and indicating by dotted lines the portion employed to form a single bag blank, and

Fig. 5, is a perspective view of the end of a bellows-folded bag blank which is subsequently formed into the bottom of the bag.

Referring to the drawings, 1 indicates a portion of the frame of the machine, which may support a roll of paper 2, (and in some instances a second roll, indicated by dotted lines at 2'). A paste receptacle is indicated at 3, and guide rollers 4, 5 and 6 may be mounted adjacent the paste receptacle for the proper direction of the paper. The machine is of the type employing the usual former plates 9 and 10, supported by the frame in any suitable number, with guide fingers 11 located near the receiving end of the former plates; such guide fingers serving to produce the desired bellows-fold at the edges of the tube being formed, and from which the bag blanks are subsequently cut.

These parts are substantially similar to parts of bag forming mechanism already in use and in the operation of my improved machine, the web of paper is conducted to the former plates in such a way that the seam to be formed is not disposed at the middle of the upper former plate, but is arranged along one side thereof, preferably at that side of the paper roll opposite the point at which the paste is applied.

In order that the web may be secured together to form a tube, one edge of the same has a line (or lines) of paste applied to the same and for this purpose I may provide a grooved paste roll 14, disposed within the paste receptacle 3; said roll being carried by a shaft 15, suitably journaled in said paste receptacle or otherwise supported. The paste-applying roll is preferably adjustably mounted on said shaft 15, and is arranged to engage one edge of the web of paper as it passes over the guide roll 6, as clearly illustrated in Fig. 1.

In order that paste can be applied uniformly to the surface of the web of paper passing over said roll 6, avoiding any possibility of

the paste roll halting or not moving with said guide roll, I provide the shaft of the latter with a pinion 16, and the shaft 15 carrying the paste roll 14 is provided with a meshing spur wheel 17, secured to the outer end of the paste roll shaft so that movement of said guide roll 6 induced by the passage of the web of paper over the same, will effect positive movement of the shaft 15 carrying 10 the paste roll and uniform contact of the same with the web of paper will be assured. The pinion 15 is preferably a broad-faced member so as to permit a range of adjustment for the spur wheel carried by the paste roll shaft 15 longitudinally of the same.

In the operation of my improved bag machine, one end of the bag blanks produced thereby, the end from which the bottom is formed, has one side of the bellow-folded tube 20. A slit at A' to provide the centrally disposed finishing flap *a* for the bottom of the bag and knives of the usual type, indicated at 19, may be arranged at a suitable point with respect to and above the former plates for the purpose of making these slits. As only one face of the tube is slit, only one set of knives are employed.

The bellow-folded tube is carried forward on the former plates and passed to the well known severing and bottom forming mechanism (not shown) by upper draft rolls 20 and 21, which cooperate with a lower roll 22, and the shafts 20^a and 22^a carrying these rolls may be geared together.

35 In order that the several draft rolls may apply their pressure evenly to the seam and avoid uneven draft due to any unevenness in the line (or lines) of the paste, I provide means for spreading the line (or lines) of 40 paste applied to the web by the paste roll. For this purpose I may provide a spreading finger comprising a flat plate, substantially flexible, indicated at 25, such plate having a support 26 carried by a stem 27, suitably mounted upon the frame 1. This stem may carry a torsion spring 28, one end of which is attached to a fixed part of the mount while the opposite end is connected with the spreader element so that the operative end 45 of the latter may be lightly held in contact with the web over the line (or lines) of paste applied thereto.

The action of this spreader is to produce a relatively thin film of the paste applied 55 and when such portion of the web reaches the draft rolls, 20 and 22, they will press it down upon the edge of the paper web which has been brought into the proper relative position by the former plates. The lower draft 60 roll is grooved at 22^b and the upper roll 20 engaging the seam partially overlies this groove so that should any portion of the paste tend to increase the thickness of the seam it may be relieved, spreading laterally into such 65 groove.

In the operation of my improved machine, the web of paper after being formed into a bellow-folded tube, in which a side seam is employed to complete the tubular formation, receives slits on one side only, indicated at 70 A', and when such bag is introduced to the bottom forming mechanism, the portion *a*, lying between said slits A', is properly manipulated and is the last secured in place to form the bottom of the bag by the application of suitable lines of paste.

In bag machines of this character, it is quite the practice to provide a double web of paper, that is to say, a web of relatively heavy paper to form the exterior of the bag, and 80 a web of paper, usually of a glazed character and much thinner, to form a lining; the two webs passing to the tube-forming mechanism as a unit and the operation upon such duplex web resulting in the formation of what are 85 known as lined bags. For this purpose, therefore, I have illustrated the paste receptacle as provided with a pair of paste-applying rolls, and it will be understood that the roll indicated at 14 may be employed to apply a line of paste to the web of paper forming the outer portion of the bag, while the roll indicated at 14^a may be employed to apply a line of paste to the web of paper employed for the lining.

95 The paste for the outer web or layer of paper is preferably applied by a grooved roll as indicated at 14, making two fine lines of paste upon the paper, and in the present instance it is these lines that are engaged by 100 the spreader to provide the wider and thinner film of paste whereby the side seam may be formed which is the part engaged by the draft rolls 20 and 22. It will be understood, of course, that the spreader may be employed 105 with each line of paste applied.

110 It will be understood, of course, that the slits A' may be formed in either face of the bellow-folded blank adjacent to the point where such blank is severed from the tube, and that slitting knives, such as those indicated at 19, for instance, may be arranged to operate from a point below the former plate 10 instead of above the same.

115 I claim:

1. The combination with a paste receptacle, a guide roll disposed adjacent thereto and means for conducting a web of paper over said guide roll, of rotating paste-applying means mounted in said paste receptacle and disposed adjacent to one edge of the web of paper and arranged to contact therewith for the purpose of applying a narrow line of paste to the outer surface thereof, means for driving said paste-applying means and the guide roll whereby the movement of one of said members will be positively transmitted to the other and the paper web moved in unison with the paste-applying means, and an overhanging member disposed at one end of 120 125 130

- the guide-roll and under slight tension positioned directly above the line of paste applied to the paper web for spreading the same into a slightly wider film.
- 5 2. The combination with a paste receptacle, a guide roll disposed adjacent thereto and means for conducting a web of paper over said guide roll, of a roll mounted in said paste receptacle and arranged to contact with said 10 web of paper; said roll having a contacting surface adapted to apply paralleling lines of paste to the outer surface of said web of paper, means for driving the paste-applying roll and the paper in unison, and means disposed at one end of the guide-roll and overhanging the paper web and in contact therewith for spreading into a continuous connected film on the web of paper the lines of 15 paste applied thereto by the roll in the paste receptacle.
3. The combination of a paste receptacle, a pair of narrow paste rolls disposed in said receptacle side by side; one of said rolls being arranged to apply two lines of paste to the outer surface of a web of paper, means including a guide roll for conducting said web of paper past the paste-applying rolls, and a spring-pressed finger positioned above and adjacent one end of the guide roll and adapted to contact with the surface of the paper web for spreading into a continuous connected film the parallel lines of paste applied by one of said paste rolls.

In witness whereof I have signed this specification.

AUGUST BECKMANN.
